[57] CLAIM

The ornamental design for a compartmented container
or the like, as shown and described.

DESCRIPTION

FIG. 1 is a perspective view of a compartmented container
or the like showing my new design;

FIG. 2 is a top plan view thereof;

FIG. 3 is a front elevation thereof;

FIG. 4 is a rear side elevation thereof;
FIG. 5 is a left side elevation thereof, the right side
elevation is similar to the left side elevation shown;

FIG. 6 is a bottom plan view thereof; and

FIG. 7 is a perspective view thereof with some covers
in open position.

FIG.1
